SOAP HOLDER

Robert D. Baca, 259 Elm St.,
San Bruno, Calif. 94066

Filed June 24, 1974, Ser. No. 482,325

Term of patent 14 years

Int. Cl. D23—02

U.S. Cl. D6—90

FIG. 1

FIG. 4

FIG _ 5

FIG _ 2

FIG _ 3

FIG _ 6

FIG. 1 is an isometric view of a soap holder embodying my new design, the bar of soap shown in broken lines is for illustrative purposes only;

FIG. 2 is a front elevation view of the soap holder of FIG. 1;

FIG. 3 is a right end elevation view of the soap holder shown in FIG. 2 (the left end elevation view is a mirror image of this right end elevation view);

FIG. 4 is a rear elevation view of the soap holder shown in FIG. 2;

FIG. 5 is a top plan view of the soap holder shown in FIG. 2; and

FIG. 6 is a bottom plan view of the soap holder shown in FIG. 2.

I claim:

The ornamental design for a soap holder, substantially as shown and described.
